GOLF CLUB SEAL AND METHOD OF MAKING
THE SAME

Kenneth Smith, Kansas City, Mo.

Application February 23, 1932. Serial No. 594,444

5 Claims. (Cl. 273—81)

This invention relates to the art of making golf clubs or similar articles where it is desired to produce a neat finish at the end of a shaft which is usually wrapped with some material 5 affording a better grip to the user.

One of the salient aims of this invention is the provision of a perforated grip for golf clubs, which grip is maintained in sealed relation with the shaft proper by a novelly formed cap created 10 by molding the same directly upon the end of the club whereby to utilize its inherent adhesive qualities and to create a desirable finish and protecting part that is pleasing in appearance, strong and durable, not likely to become loose 15 or torn away from its fixed position, and will add rather than detract from the appearance of the capped shaft.

A further object of this invention is to provide a method of applying a cap of special material, which method is unique in that it permits the application of a desirable part without changing the form of the grip or shaft; the cap may be molded directly upon the shaft and made 20 as thick as desired by successive applications of the material, all of which effectively seals together the parts of the shaft at the capped end.

A still further object of the instant invention is the contemplation of a golf club structure, wherein is embodied a perforated grip and a molded 25 cap, both of which combine to preclude dislodgment of either, all to the end of producing a highly desirable piece of golfing equipment.

It is well known in this art that grips for golf club shafts are inclined to tear away from the 30 end of the shaft and unless a suitable seal of some sort is applied, the parting between shaft and wrapping becomes exceptionally objectionable. Manufacturers of golf clubs have heretofore 35 applied many types of caps, all of which were made separately and applied through the medium of screws, adhesives or other means whereby the cap was secured in place.

In the case of metallic caps, it often became 40 necessary to provide special equipment for crimping the sides of the cap or pressing the same into place. Screw-threaded ferrules have likewise been used and it is one of the main objects of this invention to overcome the objections which 45 accompany all such structures. The exact manner of producing a cap in accordance with this method and its novel combination and form will become apparent through an understanding of the following specification, referring to the 50 accompanying drawing, wherein:

Figure 1 is a side elevation of the grip portion of a golf club embodying this invention.

Fig. 2 is an enlarged, fragmentary, longitudinal section through the upper portion of said golf club, taken on line II—II of Fig. 1.

Fig. 3 is a cross section through the capped portion of the golf club, and,

Fig. 4 is an end elevation of the same.

The method of applying and producing the cap must be understood before its relation to the 65 remaining parts of the golf club become apparent and, since such is true, the preferred manner of creating the cap will first be set down.

While this invention might be applied in capping either wood or steel shafted golf clubs, the 70 same has here been shown to be built into a golf club having the well known steel shaft 6, the grip end of which is closed by a plug 8 which is driven into shaft 6 to a point where it projects therefrom as shown in Fig. 2. The projected portion 75 of plug 8 flares outwardly and produces a head 10, the top 12 of which rises to an apex 14 by having top 12 formed to present a flat cone. About shaft 6 is wrapped a filler 16 which may be of paper or fibrous material suitable for the 80 purpose for which it is applied. This filler 16 extends slightly beyond the end of shaft 6 and thereby overlaps the head 10 of plug 8.

Around this filler 16 is placed wrapping 18 that is made of a good grade of soft leather. This 85 wrapping is applied by affixing a relatively narrow strip of leather as shown in Fig. 1, which wrapping 18 terminates just below meeting edge 20 of top 12 and head 10 of plug 8. To create an effective grip, a plurality of perforations 22 90 are formed through wrapping 18, thereby to present cavities bottomed by filler 16 or the head 10 of plug 8 when wrapping 18 is in place. Such a perforated grip not only prevents slipping or turning of the club in the hands of the player, 95 but also combines with the hereinafter described cap in the making of a unitary structure.

After the parts of the club just mentioned have been assembled in the manner described, cap 24 is produced by dipping the end of the shaft into 100 a solution of pyroxylin. After once dipping to the desired depth, a coating is formed and must be allowed to set before re-dipping to form a superimposed coating whereby the thickness of cap 24 is increased. Such dipping may be re- 105 peated as often as is necessary. After each dipping the club is hung with the dipped end down to allow surplus solution to collect at apex 14. This solution forms in a small globule and may be removed by any suitable instrument. After 110

the solution has set sufficiently to preclude running, the club is then turned right side up and the small round zone at apex 14 is smoothed before the material forming said cap 24 has hardened beyond a point where it may be molded.

In forming cap 24 in this manner, there are also created projections 26 which extend through perforations 22 wherever they underlie skirt 28 of cap 24. This feature securely bonds plug 8, 10 wrapping 18 and cap 24 and positively seals the upper end of the club. The adhesive quality of the material forming cap 24 causes an adherence to all parts contacted and there is no possibility of this cap becoming loosened without actually destroying the parts making up the club.

It is notable that the form of the end of the club is not destroyed when applying this unique cap 24. The cap is molded directly upon the end 20 and immediately assumes the contour of the underlying parts. The pleasing bevel 28' that is created by trimming wrapping 18 lends a rounded appearance and feel, and also contributes to eliminate the presence of any sharp edges or 25 bulky shoulders that might interfere in the use of the club. Such a cap blends more thoroughly with the soft feel and appearance of wrapping 18 and by virtue of its toughness, presents a protecting covering that will not burr or scuff to the 30 extent of causing sharp projections to appear.

In making up the solution into which the end of the club is dipped when producing cap 24, it is well to remember that any material such as 35 pyroxylin made up in the majority of a soluble gun cotton may be utilized. Such materials may be dissolved in a solution consisting of 50% acetone and 50% amyl acetate. The solution when ready for use should be rather thick or in a semi-liquid condition and therefore the pyroxylin or like material should be thoroughly dissolved by allowing 40 the same to soak for approximately forty-eight (48) hours. It has been found in practice that slightly warming the solution at the end of this time to prepare it for actual application completely dissolves the material and renders it easy 45 to handle.

Obviously, any pigments might be added to this solution to produce a cap of desired color and the cap may be extended down over as much 50 of wrapping 18 as is thought to be necessary or practical. No equipment other than a container for the solution and means to hang the club is necessary and since the possibilities of this in-

vention are so far reaching, it is understood that such modifications might be practiced as fairly fall within the spirit of the invention and scope of the appended claims.

Having thus described the invention, what is 80 claimed as new and desired to be secured by Letters Patent is:

1. In a golf club, a shaft; a wrapping for the shaft; a plurality of perforations formed through the wrapping; and a cap over the end of said shaft and a portion of said wrapping, said cap having integral projections extending through the said perforations underlying the cap. 85

2. In a golf club, a shaft; a wrapping for the shaft; a plurality of perforations formed through the wrapping; and a cap over the end of said shaft and a portion of said wrapping, said cap having a portion thereof extending through the perforations underlying the cap and secured to said shaft. 90

3. In a golf club, a shaft; a wrapping for the shaft; a plurality of perforations formed through the wrapping; a cap molded over the end of said shaft and a portion of the perforated wrapping having a top wall and an annular skirt 100 integral therewith; and integral projections formed on the inner face of said skirt extending into the perforations formed in said grip. 95

4. In a golf club, a shaft having an outwardly flared, frusto-conical head terminating in a flat- 105 tened cone with its apex disposed on the longitudinal central axis of the head; a wrapping for the shaft; and a sealing cap, of plastic material and of substantially uniform thickness throughout, over the end of said shaft and adhering to 110 the exposed surfaces of both shaft and wrapping underlying the same, said cap including a depending annular skirt having an inside diameter at the annular free edge thereof that is appreciably less than the inside diameter thereof at its 115 base.

5. In a golf club, a shaft having an outwardly flared head; a wrapping for the shaft; and a sealing cap, of plastic material, of substantially uniform thickness throughout, over the end of 120 said shaft and adhering to the underlying surfaces of both shaft and wrapping, said cap comprising a depending annular skirt having an inside diameter at the annular free edge thereof that is appreciably less than the inside diameter 125 thereof at the base of the skirt.

KENNETH SMITH.
